MOTOR STARTING WINDING SWITCH

Albert J. Hedquist, Ferry Road, New Brunswick, Canada, and Leo A. Mitchell, Newcastle, New Brunswick, Canada

Filed July 29, 1958, Ser. No. 751,696
3 Claims. (Cl. 200—87)

This invention relates to electric motors, and more particularly to a starter for an electric motor.

The object of the invention is to provide a cutout switch for an electric motor such as a split phase motor, and wherein according to the present invention a magnetic field obtained from the motor current is used.

Another object of the invention is to provide an electric motor starting switch which can be mounted either on the inside or the outside of the motor and wherein the device has no attachment to the rotor, the present invention being adaptable to any size of split phase motor and wherein the device is easy to install and requires no service or adjustment.

A still further object of the invention is to provide a motor attachment which utilizes the motor current and a magnetic field for the desired switching action.

A further object of the invention is to provide an electric motor starter which is extremely simple and inexpensive to manufacture.

Other objects and advantages will be apparent during the course of the following description.

In the accompanying drawings, forming a part of this application, and in which like numerals are used to designate like parts throughout the same:

FIGURE 1 is an end elevational view illustrating the electric motor starter of the present invention, and showing the motor shaft in section.

FIGURE 2 is a side elevational view of the device of FIGURE 1.

FIGURE 3 is a plan view of the assembly of FIGURES 1 and 2.

FIGURE 4 is a wiring diagram illustrating the present invention.

Referring in detail to the drawings, the numeral 10 indicates the electric motor starter of the present invention, and it will be seen that the motor starter or switch 10 includes a center support member or disk 11 which is provided with a central opening 12 through which may extend a shaft such as the motor shaft 13, FIGURES 1 and 2.

Extending from the support member 11 and connected thereto is a plurality of spaced apart brackets 14. The numerals 15, 16 and 17 indicate wires or conductors, while the numeral 18 indicates a coil which has a core arranged therein.

The numeral 20 indicates a stationary base which is secured to the core 19 in any suitable manner, and a pair of spaced apart contacts or points 21 are connected to the base 20. The numeral 22 indicates a movable armature which has one end pivotally or hingedly connected to the core 19 as at 23. The other end portion of the armature 22 is mounted for movement into and out of engagement with an end 24 of the stationary core 19.

Mounted below the armature 22 is an insulated strip 25, and arranged below the strip 25 and connected to the armature 22 is a terminal or contactor 26. The terminal 26 is mounted for movement into and out of electrical engagement with the contacts 21.

Extending from an end of the armature 22 and connected thereto or secured thereto in any suitable manner is an ear 27, and the numeral 28 indicates a resilient means or coil spring which is connected to the ear 27. A securing element such as a bolt 29 extends outwardly

2

from the core 19, and a nut 30 is arranged in threaded engagement with the securing element 29. The numeral 31 indicates a clamp which is provided with a slot 32, and the slot 32 has the securing element 29 extending therethrough. The provision of the slot 32 permits the nut 30 to be loosened so that the clamp 31 can be moved to different adjusted positions, and then the nut 30 can be tightened so that the tension of the coil spring 28 can be varied or regulated as desired.

10 Referring to FIGURE 4 of the drawings, there is illustrated schematically the wiring diagram for the present invention, and it will be seen that numeral 33 indicates a conventional motor which includes the usual windings 34 and 35. The numeral 36 indicates power input or power supply lines which may have a suitable switch 37 connected thereto.

From the foregoing, it is apparent that there has been provided a device which is especially suitable for starting electric motors such as the split phase type, and wherein there is utilized a magnetic field obtained from the motor current.

It is known that a split single phase motor when starting will draw from three to four times as much current as when it has gained its normal speed. According to

25 the present invention this current is utilized to close a switch which is connected in series with a starting winding such as the winding 35 in the motor 33. The heavy starting current produces a magnetic field which closes the switch by moving the armature 22 against the tension

30 of the spring 28 so as to energize the starting winding whereby the motor starts and gains speed. As the motor approaches normal speed, the current drops, so as to weaken the magnetic field.

Then, the tension of the spring 28 opens the switch so as to cut the starting winding out of the circuit. There is a great margin of magnetic attraction between the starting and running which permits the spring 28 to break contact. It is believed obvious

35 that this is the proper way of getting control, rather than depending on centrifugal force to open the switch which is the conventional way, where a switch is mounted on the inside of an end bell and the prior devices are very complicated and are mounted on the rotor and spin with the rotor which has a tendency to block or fly apart or fail to reach the switch or fail to withdraw from the same which often results in burned out windings or the like.

The present invention can be mounted from the inside or outside on the end bell and it has no attachment to the rotor, and it will fit any size split phase motor and is very simple and cheap to manufacture and is also easy to install and requires no service or adjustment. A main point of the present invention is that the motor current is utilized as well as a magnetic field for the desired switching.

55 The terminals 26 are insulated from the armature 22 by means of the insulated strip 25, and these terminals 26 are arranged so that they will be properly aligned with respect to the contacts 21. The contacts 21 are insulated from each other. The armature 22 does not carry current and as previously described, the slot 32 permits the tension on the spring 28 to be adjusted or regulated as desired.

60 When the line switch 37 is closed, the rush of motor current through the running winding 34 and also through the series coil 18 is many times the value of the normal run. The magnetic attraction overcomes the spring tension 28 to thereby close the terminals 26 on the contacts 21 which completes the circuit for the starting winding 35. As the motor gains speed, the current diminishes so that the coil 18 gets weaker and finally the spring 28 overcomes the attraction of the coil 18 to thereby cut or move the starting winding out of the circuit as is the

practice. With the prior devices or earlier systems the cutout switch had to be mounted within the motor which is dangerous in certain locations due to sparking at the points. With the present invention the cutout switch 10 can be mounted at a great distance from the motor or it can be mounted from within the motor.

The device can be used on split phase motors of different sizes or horsepower and the only requirement is an initial adjustment for each size motor. The unit can be mounted inside or outside the motor with suitable clamps and when mounted inside, the rotor shaft 13 extends through the unit which is clamped to the end bell. This conserves space which is very important and it can be used on existing motor frames without any change.

Furthermore, the instant starting effort of a motor when using the present invention is from 30% to 50% greater with or without starting capacitors. This is believed due to the slight time delay of current through the action of the switch for the starting winding which is a highly advantageous factor or point.

In motors such as fractional horsepower electric motors, there is a type which is called a split phase squirrel cage motor, and the rotor of this type of motor would resemble a squirrel cage if all of the iron was removed, with copper bars and end rings exposed. Such motors have two windings in the motor field, one of which is called the running winding which is the only winding used after the motor has gained its speed. A motor of this type with only the running winding is not able to start from rest so that a second winding is found in this motor field which is called the starting winding. This winding is placed in such a way in the motor field that it splits the single phase and creates a starting torque and when the motor is up to speed, this winding is not needed, therefore, it is cut out of the circuit by a centrifugal switch which is in series with the starting winding. Switch points are generally mounted on the inside of the end bell and a mechanical device is mounted on the rotor shaft which is operated by centrifugal force so that this is often referred to as a centrifugal switch. The present invention will take the place of the centrifugal switch so that it will be seen that in effect the present invention is a starting winding switch for split phase motors utilizing motor current and magnetic field for operation.

The mounting adaptor 11 can be made of a suitable material such as Bakelite, plastic, fiber board, or a suitable insulating material to which the unit is secured by metal brackets 14, or by any suitable attaching means. The core 19 is adapted to be made from a suitable material such as laminated steel such as that type which is used for small transformers, A.C. motors or relays, and is curved to a semi-circle or horseshoe shape and riveted together. The end 23 of the core 19 is extended and bent and is provided with a slot to receive the armature 22 to serve as a hinge and a pivot may be used. The base 20 is made from a non-magnetic, non-conductive material which does not conduct electric current. When armature 22 is opened by tension of the spring 28, the air gap should not be too great and should be just sufficient to break contact between the fingers 26 and points 21. The finger contacts 26 are split at one end but are electrically one, and the split serves to give better alignment with the contact points 21, which the members 26 are bridging when closed. The members 26 are electrically insulated from the armature 22 at the anchorage, and the strip 25 is extended to prevent accidental contact with the free end when being attracted to the end portion 24 by the magnetic field. The electrical circuit is entirely insulated from the magnetic circuit.

As indicated by the showing in FIGURE 4, the ends of the lines or wires are brought out to a terminal box on the motor. The lead 16 and point 21, and one end

of the series coil 18 are common. The other point 21 has a lead 15 connected to it. At the other end of the coil 18 is the lead 17. The leads 15, 16 and 17 are made to reach motor terminals when mounted on the inside or outside of the motor.

The contactor 26 completes the circuit through the points 21 when attracted by action of motor current through the series coil 18.

When the line switch 37 is open, the armature is held open by tension of the spring 28. When the line switch 37 is closed, a rush of current through the lead 16 which is connected to one end of the series coil 18, from which it flows through lead 17 to motor running winding 34 and back to line switch 37. The rush of current through member 18 magnetizes the core 19 which attracts armature 22 toward the pole piece 24 and in so doing the contactor 26 closes the circuit through points 21 to lead 15, through starting winding 35 back to switch 37 which completes the circuit through the starting winding and motor so that the motor will start; as the motor approaches full speed the current drops to normal in running winding which is in series with the coil 18 and hence the magnetic strength in the core 19 is weaker. The spring 28 opens the armature at 24 which breaks the circuit through points 21 which cuts the starting winding out of the circuit as it is no longer needed until the next start. When the unit is connected to a motor, an initial adjustment of the spring 28 is all which is required.

It is to be noted that according to the present invention an electromagnet semi-circular or U-shaped formation surrounds or partly surrounds the motor shaft when mounted inside of a motor housing and this requires less space to allow the unit to be used within existing motor frames. There is a very limited space due to overhang of windings and fan blades on rotor which renders any other shape impractical. Due to the shape of this unit a magnet wire large enough for $\frac{3}{4}$ H.P. may be used for series coil 18. This would handle split phased motors from the lowest up including $\frac{3}{4}$ H.P. The only requirement would be a coil spring 28 suitable and in proportion to a large change in H.P., that is a spring with greater tension for the group of highest H.P.

As the series coil contains only twenty-five turns the loss is practically zero and there is no interference.

Minor changes in shape, size and rearrangement of details coming within the field of invention claimed may be resorted to in actual practice, if desired.

We claim:

1. In a device of the character described, a circular support member provided with a central opening for the projection therethrough of a shaft, a plurality of spaced apart brackets connected to said support member, a coil connected to said brackets, wires connected to said coil, a core having its major portion arranged within said coil, a base connected to said core, a pair of spaced apart points extending from said base, an armature having one end pivotally connected to a portion of said core, the other end of said armature being mounted for movement into and out of engagement with another portion of the core, an insulated strip mounted below said armature, contactors carried by said armature and arranged below said insulated strip, and said contactors being mounted for movement into and out of engagement with said points.

2. In a device of the character described, a circular support member provided with a central opening for the projection therethrough of a shaft, a plurality of spaced apart brackets connected to said support member, a coil connected to said brackets, wires connected to said coil, a core having its major portion arranged within said coil, a base connected to said core, a pair of spaced apart points extending from said base, an armature having one end pivotally connected to a portion of said core, the other end of said armature being mounted for movement into and out of engagement with another portion of the

core, an insulated strip mounted below said armature, contactors carried by said armature and arranged below said insulated strip, and said contactors being mounted for movement into and out of engagement with said points, and resilient means connected to said armature.

3. In a device of the character described, a shaft, a circular support member provided with a central opening for the projection therethrough of said shaft whereby said support member surrounds said shaft, a plurality of spaced apart brackets connected to said support member, a coil that is wound crosswise or around a complete magnetic path connected to said brackets, wires connected to said coil, a core having its major portion arranged within said coil, a base connected to said core, a pair of spaced apart points extending from said base, an armature having one end pivotally connected to a portion of said core, the other end of said armature being mounted for movement into and out of engagement with another portion of the core, an insulated strip mounted below said armature, contactors carried by said armature and arranged below said insulated strip, and said contactors being

5

mounted for movement into and out of engagement with said points, and resilient means connected to said armature, said resilient means comprising a coil spring, an ear extending from said armature and connected to one end of the coil spring, a securing element extending from said core, a clamp connected to the other end of the coil spring, said clamp being provided with a slot for the projection therethrough of the securing element.
